MOUNTING BRACKET

George Geisinger, Elizabeth, N.J., assignor to The Thomas & Betts Co., Elizabeth, N.J., a corporation of New Jersey

Filed Aug. 26, 1965, Ser. No. 86,718

Term of patent 14 years

(Cl. D54—1)

The broken lines are for illustrative purposes only.

I claim:

The ornamental design for a mounting bracket, as shown and described.
